UNITED STATES PATENT OFFICE.

WILLIAM SIMON, OF NORTH SYDNEY, NEW SOUTH WALES, AUSTRALIA.

DEVICE FOR USE WITH LACES OF BOOTS AND SHOES.

Application filed October 4, 1924. Serial No. 741,606.

To all whom it may concern:

Be it known that I, WILLIAM SIMON, a subject of the King of Great Britain, residing at 472 Miller Street, North Sydney, 5 New South Wales, Commonwealth of Australia, have invented certain new and useful Improvements in or Relating to Devices for Use With Laces of Boots and Shoes, of which the following is a specification.

10 This invention has reference to devices for use with the laces of boots and shoes.

In connection with the laces of boots and shoes and the manner in which they are tied or fastened for firmly securing the boot or shoe to the foot, it is generally the practice 15 to leave the ends either in the form of a free bow or free single ends, which in many instances present an untidy appearance and invariably the tying or knotting comes loose 20 rendering the boot or shoe uncomfortable during wear.

According to this invention such general untidy appearance of boots and shoes is entirely obviated by means of a device capable 25 of being temporarily engaged with the aforesaid free bow or ends and of being passed underneath the upper of the boots or shoes for disposing beneath such upper the free bow or ends in a flat and comfortable 30 condition, the device being adapted to be disengaged from the said bow or ends upon withdrawal thereof from beneath the said upper. To this end the device is in the 35 form of a flat or rounded member suitable for the purpose and is provided with a channel or recess capable of engagement with the said free bow or ends. If desired, the device may be provided with a blunt or rounded extension adapted to facilitate 40 the introduction of the device beneath the upper of the boot or shoe. Such extension is preferably so shaped as to serve as a guard or shield to the channel or recess and prevent the opposite jaw of the channel or 45 recess damaging the sock or stocking by becoming engaged therewith when the device is being introduced beneath the said upper. The device may also be provided with a hook for engagement with the lace or the 50 inturned portion thereof when it is desired to loosen and remove the boot or shoe. The device facilitates carrying out an improved method of arranging in position the free bow or ends of the lace such method consisting in arranging the free ends in a flat 55 condition beneath the front of the upper of

a shoe by engagement of the free bow or ends with the channel or recess, sufficiently introducing the channelled or recessed portion of the device beneath front of such upper to dispose the free bow or ends in the flat condition and thereafter withdrawing the device, the commencement of such withdrawal effecting the disengagement of the channel or recess from the free bow or 60 ends.

In order that the said invention may be clearly understood and readily carried into effect the same will now be fully described by way of example with reference to the 70 accompanying drawings, in which:

Figures 1, 2 and 3 are respectively transverse section, side elevation and plan of one constructional form of the device, according 75 to this invention.

The device is provided with the channel or recess *b* and the extension *a* the latter forming a continuation of the jaw on one side of the channel or recess *b* and being curved inwardly towards the opposite jaw 80 to serve as a guard to such channel or recess *a*. The opposite end of the device to that provided with the extension *b* is formed with a hook *c*. The device as a whole is formed with rounded edges and the hook *c* 85 and the jaw of the channel or recess is also rounded off to avoid the presence of parts liable to engage with the sock or stocking, while to facilitate using the device the extension *a* is formed with a rounded terminal 90 end and is approximately of elliptical or circular cross section and of varying width lengthwise.

The device may be made of any suitable material to any desired size. Although 95 only one construction of the device is hereinbefore described with reference to the accompanying drawings it will be understood that modifications may be made therein without departing from the nature of the 100 invention.

In making use of the device the free end of the lace is engaged in the channel or recess *b* and introduced beneath the upper of the boot or shoe by means of the rounded extension *a*, the device being moved a sufficient distance lengthwise beneath the said upper to arrange the free end in a flat condition. The reversal of the movement 105 brings about disengagement of the device 110 from the free end of the lace and its removal from beneath the said upper. By

the insertion of the hook underneath the said upper the free end of the lace can be engaged therewith and withdrawn.

What I claim and desire to secure by Letters Patent of the United States is:—

1. A device for use with boot and shoe laces comprising a member formed with a recess capable of engagement with a free part of the lace and with an extension on each side of the recess, the extension on one side of the recess being of greater length than that on the opposite side.
2. A device for use with boot and shoe laces comprising a member provided with a recess having an extension on each side thereof, the extension on one side being of curved rounded form and of greater length

than that on the opposite side and serving as a guard to the recess.

3. A device for use with boot and shoe laces having rounded edges, a recess for engagement with a part of the lace the recess having on each side an extension, the extension on one side of the recess being of greater length than that on the opposite side and of approximately round cross section.

4. A device for use with boot and shoe laces comprising a member formed with rounded edges and having at one end a recess and an extension of approximately round cross section on one side of the recess and at the other end a hook.

WILLIAM SIMON.
